UNITED STATES PATENT OFFICE.

EDGAR P. WATROUS AND LEROY VAN BENSCHOTEN, OF GROTON, NEW YORK, ASSIGNEES TO CONGER MANUFACTURING COMPANY, OF SAME PLACE.

STACKER FOR THRESHING-MACHINES.

SPECIFICATION forming part of Letters Patent No. 681,007, dated August 20, 1901.

Application filed January 30, 1901. Serial No. 45,324. (No model.)

To all whom it may concern:

Be it known that we, EDGAR P. WATROUS and LEROY VAN BENSCHOTEN, of Groton, in the county of Tompkins, in the State of New

5 York, have invented new and useful Improvements in Stackers for Threshing-Machines, of which the following, taken in connection with the accompanying drawings, is a full, clear, and exact description.

10 Our invention relates to improvements in stackers for threshing-machines, and particularly to the means for expelling and stacking the straw, chaff, &c., accumulating from the machine.

15 The object of this invention is to produce a simple, compact, and practical device which is adapted for use in low barns and other inconvenient and limited spaces, where it is necessary to discharge and stack the straw, 20 chaff, &c., in cramped places at either side of or in any direction from the machine.

25 The further object is to provide means whereby an operator of ordinary intelligence may readily manipulate the device from the floor upon which the machine rests for directing the discharge of the straw and chaff to any desired locality within the range of the stacker.

To this end the invention consists in the 30 combination, arrangement, and detail construction of the parts of a stacker, as hereinafter fully described, and pointed out in the claims.

Referring to the drawings, Figure 1 is a 35 longitudinal vertical sectional view of our improved stacker and the adjacent portion of a threshing-machine to which it is attached, the outer end and hood of the stacker being shown in elevation and the gear-case being 40 omitted to avoid confusion of the more essential parts. Fig. 2 is a detail plan view of one of the supports for the discharge-chute. Fig. 3 is a perspective view of the device seen in Fig. 1, portions of the fan-casing 45 being broken away and a gear-case and cross-bar being omitted for disclosing the interior and underlying parts of the invention. Fig. 4 is a detail sectional view of the driving gears for the fan, showing the inclosing case 50 and bearings for the gears and shafts in section. Fig. 5 is a perspective view of one

of the detached elbow-sections seen in Figs. 1 and 3.

Similar reference characters indicate corresponding parts in all the views.

This invention consists, essentially, of a tilting chute or discharge-conduit A, having its free end provided with separated annular shoulders a a; a hood B, pivoted at b to an annular ring b', which is revolubly mounted 55 on the outer end of the chute A between the shoulders a a, and a fan C, revolubly mounted in an independently-revolving fan-case D. The chute or discharge-conduit A is preferably composed of end and intermediate sections t, i', and u, telescoping with each other, the inner end of the inner section t being hinged at c' to the adjacent portion of the fan-case, which in turn is revolubly supported by the adjacent end of the threshing-machine frame E, a portion of which is seen in Figs. 1 and 3. This inner section t forms a support for the intermediate and outer sections u and i', the section u being movable lengthwise of the outer end of the 70 section t and the section i' being movable by hand lengthwise of and upon the outer end of the section u for removing the same, if desired, it being detachably interlocked with the section u. The shoulders a a are formed 75 upon the outer end of the section i' and serve to hold the ring b' from endwise movement or displacement. The pivotal pins b project laterally from opposite sides of the ring b' and form suitable trunnions for supporting the hood B and permitting its oscillatory movement. The hood B usually consists of a semicylindrical shell, having its inner end mounted on the trunnions b and provided with a reinforcing-band formed with depending ears V and its outer end terminating in a substantially semiconical deflector for diverting the straw, chaff, &c., from the mouth of the chute in any desired direction, it being understood that said hood is revoluble with 90 the annular ring b'. Suitable springs W are interposed between the ears V and ring b' for forcing and holding the hood B in its normal upwardly-inclined position.

The means for controlling the position of 100 the hood B generally consists of a rope or cord Y, having corresponding ends passed in

opposite directions around the pulleys X on the chute A and secured to the ears V of the hood B, the opposite ends of said cords being adapted to be secured to a fastening member 5 p, also provided on the chute A, in proximity to its inner end.

The means for supporting the free end of the chute A preferably consists of a tubular arm N and a hoisting cable or rope d', the 10 arm N being pivotally secured at one end to suitable ears l' on the lower face of the inner end of the discharge-chute A and having its outer free end provided with rollers or spools T, having concave bearing-faces upon which 15 the lower face of the chute A normally rests. The arm N usually extends outwardly beyond the inner end of the intermediate chute-section u, and the rollers T are normally engaged with the lower face of said intermediate section and serve as a roller-bearing for 20 supporting the section u and permitting the same to be readily and easily moved lengthwise of the section t when desired to extend or shorten the chute.

25 The means for moving the chute-section u lengthwise of the section t preferably consists of a sprocket e and a chain i, connected to the chute u, the sprocket being mounted on a spindle journaled in the ears l' and driven 30 by a suitable hand-crank or equivalent device, Figs. 2 and 3, and the chain i being passed over the sprocket and a suitable idler f on the supporting-shaft v of the rollers T. The opposite ends of the arm N are usually 35 bifurcated to receive the sprocket e and rollers T, respectively, the inner end of said arm being mounted on the sprocket-shaft supported by the ears l' and the outer end being arranged to support the spindle v and the 40 rollers T and idler f mounted thereon. A reinforcing-band P encircles the inner end of the section u and is provided with depending ears or lugs d, upon which is mounted a revoluble roller R, having a concave face for receiving and supporting the intermediate portion 45 of the arm N and preventing any sag or bind between the sections u and t.

The means for raising and lowering the free end of the chute A generally consists of 50 a cord or cable d', one end of which is connected to a suitable bail or loop U, pivotally connected to arms mounted on the shaft v of the arm N, and its other end is passed over suitable sheaves or pulleys, which are connected, respectively, to the bail U and upper part of the threshing-machine E. This latter end of the cord d' is secured to and adapted to be wound upon a drum, which is provided with a crank-arm o and a ratchet-wheel 55 60 and is held in its adjusted position by a pawl normally forced into engagement with the ratchet-wheel by a spring s'.

It is evident from the foregoing description that the chute A may be readily rocked upon 65 its pivotal support or hinge c' by the cable d' and crank o, and that the hood B may also be rocked upon the pivots b or rotated upon

the end of the section i' by the cable Y; but it is obvious that other equivalent means may be employed for effecting these results and 70 that other devices than the one described may be used for the support and extension of the chute, if desired.

In order to form a continuous chute and at the same time permit the same to be tilted to 75 any desired angle, we generally provide a flexible elbow, consisting of a series of overlapping split sections M, pivoted to the hinge c' and adapted to telescope with each other, the end sections being arranged to telescope 80 with the adjacent portions of the fan-case and chute-section t, respectively. These elbow-sections M are each provided at their meeting edges with apertured ears for receiving the pivotal pin of the hinge c', said ears being interposed between the hinge-sections and concealed thereby and are also formed at their opposite edges with oppositely-turned flanges l for limiting the expansion of the elbow, one of said flanges of each section being 85 provided with lateral shoulders k, which, together with the flanges l, serve to prevent undue movement of the sections M and to form a substantially dust-proof joint. The outer flange of each section M is arranged to lap 90 upon the inner face of the next adjacent section, it being understood that the portion of the fan-case D adjacent to the chute is formed with a discharge-opening aligned with the chute and is provided with an annular shoulder projecting into the adjacent section M. The inner end of the chute-section t is also provided with a flange similar to the flanges l and is adapted to inclose the adjacent end of the outer section M. In order to relieve 95 the strain upon the elbow-sections M incidental to undue upward movement of the chute, we provide a suitable stop, as a chain 100 105 110 115 120 125 130 135 140 145 150 155 160 of the rod G and having its lower face resting upon the bearing h and its upper face formed with an oil pocket or recess h'. The upper end of the support or sleeve F is provided with a circular toothed rack arranged in proximity to the lower face of the fan-case, which is provided with a spring-actuated latch or sliding bolt adapted to engage the teeth of the rack for holding the fan-case in its adjusted position and permitting the same to be rotated for moving the chute laterally at any angle with the machine. The frame of the machine is provided with a hopper or funnel-shaped inclosure having a circular opening in its base and provided with an annular flange surrounding said opening. The fan-case D is substantially circular in form, is interposed between the base of the hopper and the support F, and is provided with circular openings in its upper and lower walls alined with each other and with an additional opening in its peripheral wall alined with the chute A. The lower wall of the fan-case is provided with a plate H, having a supporting-guide for the latch I, and is formed with an annular bearing-face resting on the upper face of the sleeve F and with a hollow depending hub g', projecting into the sleeve F and terminating above the bearing h.

The upper wall of the case D is provided with an annular flange encircling the opening in said wall and surrounding the depending annular flange at the base of the hopper of the machine, thus forming a substantially dust-proof connection between said hopper and the fan-case and permitting the straw, chaff, &c., to be readily discharged from the machine to the fan-case, these flanges also serving as a bearing for the upper portion of the revolving fan-case and to relieve the strain upon the sleeve F. The upper and lower portions of the sleeve F are provided with annular bearings engaged with the peripheral faces of the hub of the plate H for additionally supporting the fan-case, the intermediate portion of said sleeve F between the latter bearings being usually formed of greater diameter than the hub of the plate H for forming an oil-well j, which, together with the oil-recess h', is adapted to hold a lubricant for the bearings adjacent thereto. The fan c may be of any desired form or size for drawing the straw, chaff, and dust through the hopper of the machine into the fan-case and forcing the same outwardly through the chute A and usually consists of a series of blades mounted on a suitable hub, which is secured to a revolving tubular shaft Z. This tubular shaft or sleeve Z encircles the hanger-rod G, extends through the openings in the lower and upper walls of the fan-case D, and is rotated by gears L, one of which is secured to the upper end of the sleeve or hollow shaft Z and the other is secured to a suitable driving shaft a', Figs. 3 and 4, which is generally driven by suitable cone-pulleys (not illustrated) for permitting differential speeds for

the fan c. These gears L and the adjacent ends of the shaft a' and Z are preferably inclosed in a dust-proof case w, depending 70 from the bar K and secured thereto, the walls of said case being provided with antifriction-bearings for supporting the adjacent ends of the shafts a' Z.

The lower end face of the hollow shaft Z 75 and the adjacent upper face of the bearings h are each provided with an annular groove for receiving antifriction-balls g, which support the revolving shaft Z and the mechanism mounted thereon, and the sleeve F and cap 80 h are provided, respectively, with an oil-supply cup and a drainage-cock leading to and from the bearing g. As previously stated, the hollow shaft Z extends through the hub of the plate H, is formed of less diameter 85 than the interior of said hub for forming suitable oil-pockets, and is encircled by an annular packing-ring s, formed of felt or similar material, for preventing the accumulation of dust in the bearings g, the upper end of 90 said sleeve Z being also closed by the dust-proof casing or cap w.

In the operation of our invention the latch I is withdrawn from engagement with the rack of the sleeve F, the fan-casing is rotated for moving the chute A laterally to the desired position, the latch I is then permitted to engage the teeth of said rack for locking the fan-case from further movement, the chute A is extended or shortened by the 100 sprocket e and chain i and tilted to the desired position by the cable d' and crank o, and the hood B is then rotated or tilted by the cord or cable Y for additionally directing the discharge of the straw, chaff, &c., from the 105 machine. It is obvious, however, that when desired to spread the straw, &c., over a considerable area the latch I may be permanently withdrawn from the rack and the fan-case rotated or rocked by hand or by any mechanical means. (Not necessary to herein illustrate or describe.)

The operation of our invention will now be readily understood upon reference to the foregoing description and the accompanying 115 drawings, and it will be noted that some change may be made in the detail construction and arrangement of the parts of our invention without departing from the spirit thereof.

Having thus described our invention, what we claim, and desire to secure by Letters Patent, is—

1. A stacker for threshing-machines comprising a fan-case, a hauger suspended from 125 a portion of the machine above the fan-case, and a revoluble fan carried by the hauger.

2. A stacker for threshing-machines comprising a sleeve having a vertical opening or bearing, a fan-case provided with a depending hub journaled in said bearing, and a revoluble fan suspended from a portion of the machine above the case. 130

3. A stacker for threshing-machines com-

- prising a horizontal bearing and a raised surface surrounding the bearing for forming an oil-cup, a fan-case revolvably mounted on the bearing, a hanger secured to the machine 5 above the bearing, and a revolvable fan carried by the hanger.
4. A stacker for threshing-machines comprising a sleeve having a vertical opening enlarged at its intermediate portion for forming 10 separated bearings and an interposed oil-pocket, a fan-case having a central hub journaled in said bearings, a hanger secured to the machine above the case and extended downwardly through said case and a fan 15 mounted on the hanger.
5. A stacker for threshing-machines comprising a support and a fan-case journaled on the support, one of said parts having a circular toothed rack and the other being provided 20 with a latch for the purpose described, a fan, and means above the case and connected to the fan for rotating the same.
6. A stacker for threshing-machines comprising a support having a circular toothed 25 rack, a fan-case journaled on the support and provided with spring-actuated means for engaging the rack and holding the same in its adjusted position, a shaft extending through the case and driven from its upper end and 30 a fan secured to the shaft.
7. A stacker for threshing-machines comprising a sleeve having a vertical opening enlarged at its intermediate portion for forming 35 separated vertical bearing-faces and an interposed oil-pocket, said sleeve being also provided, with an oil-cup in its upper face and with peripheral teeth, a fan-shaft extending through the opening and provided with a fan, driving means connected to the upper end of 40 the shaft, a fan-case resting on the upper face of the sleeve and provided with a hub depending into the opening and engaged with said vertical bearing-faces of the support, and a latch on the case for engaging said peripheral teeth.
- 45 8. A stacker for threshing-machines comprising a frame having separated upper and lower bearings, a fan-case interposed between said bearings and journaled thereon, a revolvable fan in said case and means above the upper bearing for rotating the fan.
9. A stacker for threshing-machines comprising a frame having separated upper and 50 lower bearings, a fan-case interposed between said bearings and journaled thereon, a revolvable shaft extending through the case and provided with a fan, and movable means for holding the case in its adjusted position and for permitting its revolvable movement.
- 55 10. A stacker for threshing-machines comprising a bearing, a revolvable tubular shaft mounted on the bearing, a fan secured to the shaft, bearing means connected to the shaft above the fan, and a revolvable fan-case in- 60 closing the fan.
11. A stacker for threshing-machines com- 65
- prising a bearing, a revolvable upright shaft mounted on said bearing, a fan secured to the shaft, and a case inclosing the fan and provided with inlet and discharge openings, the 70 fan-shaft extending through said openings and driven from its upper end.
12. A stacker for threshing-machines comprising a fixed bearing and an upright revolvable tube, balls interposed between the bearing and the adjacent end face of the tube, for the purpose described, a fan secured to the tube, a case inclosing the fan and provided with inlet and discharge openings and means connected to the upper end of the tube for 80 rotating the same.
13. In a stacker for threshing-machines, a fan-case, a revolvable tubular fan-shaft and a fan mounted on the shaft in combination with a fixed hanger-rod having a bearing engaged 85 with the lower end face of the tubular shaft for the purpose set forth.
14. In a stacker for threshing-machines, a fan-case, a revolvable tubular fan-shaft and a fan mounted on the shaft in combination with 90 a fixed hanger-rod passed through the shaft and provided with a bearing engaged with the lower end of the shaft for the purpose described.
15. In a stacker for threshing-machines, a 95 fan-case, a revolvable tubular fan-shaft and a fan on the shaft, in combination with a fixed hanger-rod passed through the shaft and provided with a bearing engaged with the lower end of the shaft for the purpose described, 100 and means connected to the upper end of the shaft for rotating the same.
16. In combination with the frame and fan-case of a threshing-machine, a hanger-rod suspended from the frame and having its lower 105 end provided with an adjustable bearing, a tubular fan-shaft encircling the rod and supported on said bearing, a fan secured to the shaft, and means for rotating the shaft.
17. In a stacker for threshing-machines the 110 combination with a support having a vertical opening, of a fan-case provided with a hollow hub journaled in the opening, a bearing at the lower end of the opening, a tubular shaft mounted on said bearing and extending upwardly through the hub and fan-case, a fan secured to the shaft, and means connected to the upper end of the shaft for rotating said shaft.
18. In a stacker for threshing-machines the 115 combination with a support having a vertical opening, of a fan-case provided with a hollow hub journaled in the opening, a bearing at the lower end of the opening, a tubular shaft mounted on said bearing and extending upwardly through the hub and case, said hub being formed with internal oil-chambers surrounding the shaft, a fan secured to the shaft, and means connected to the shaft above the case for revolving the shaft.
19. In a stacker for threshing-machines, the 120 combination with a support, of a fan-case

journalized on the support and provided with openings in its upper and lower walls, a tubular shaft extending through said openings, a hanger-rod extending through the shaft and provided with an adjustable bearing at its lower end for supporting the shaft, and means connected to the upper end of the shaft for rotating the same.

20. A stacker for threshing-machines comprising a fan-case having inlet and discharge openings, a tilting chute hinged to the case, and an elbow consisting of overlapping split sections connecting the case and chute and having their meeting ends turned outwardly and hinged to a common axis and a flexible stop also connecting the adjacent portions of the case and chute.

21. A stacker for threshing-machines comprising a fan-case having inlet and discharge openings, a tilting chute hinged to the case, an elbow consisting of split sections telescoping with each other and having their meeting ends mounted on the hinge-pin, the hinge being extended to conceal said meeting ends.

22. A stacker for threshing-machines comprising a fan-case having inlet and discharge openings, a tilting chute, a hinge connecting the case and chute and provided with a recess and a hinge-pin, and an elbow consisting of a series of split sections connecting said case and chute and having their meeting ends mounted on said pin within the recess of the hinge and concealed thereby.

23. In a stacker the herein-described elbow-section consisting of a split band having their meeting ends provided with separated substantially parallel ears and annular flanges projecting in opposite directions from the opposite edges of the band for the purpose set forth.

24. In a stacker the herein-described elbow-section consisting of a split band having separated ears and annular flanges projecting in opposite directions from the opposite edges of the band for the purpose set forth, one of said flanges being provided with laterally-projecting stop-shoulders for the purpose described.

25. A stacker for threshing-machines comprising a fan-case and a tilting chute having their adjacent edges provided with flanges, a hinge connecting the case and chute, one of the hinge-sections being provided with a recess for receiving and partially inclosing the other section, an elbow consisting of a series of split bands telescoping with each other and connecting said chute and case, said bands having their meeting ends provided with ears projecting into the recess between the ends of the hinge-sections and concealed thereby

and having oppositely-projecting flanges for 60 limiting the expansion of the elbow.

26. In a stacker for threshing-machines, a tilting chute composed of telescoping sections, an arm pivoted to one of said sections and provided with a roller-bearing for the adjacent 65 section.

27. In a stacker for threshing-machines, a tilting chute composed of telescoping sections, an arm pivoted to one of said sections and provided with a roller-bearing for the adjacent 70 section, and a movable chain or belt connected to the latter section for the purpose described.

28. In a stacker for threshing-machines, a tilting chute composed of telescoping sections, 75 an arm having one end mounted on the lower face of one of the sections and provided with a sprocket and its other end provided with a roller-bearing engaging the lower face of the adjacent section, and means connected to the 80 sprocket and roller-shaft and to the latter section of the chute for moving said latter section and a roller carried by the inner end of the movable section and engaged with the lower face of said arm for the purpose described. 85

29. The combination with the frame of a threshing-machine, of a tilting chute, a drum revolvably mounted on the chute, means for controlling the movement of the drum, a roller-bearing for the chute, a bail pivotally connected to the axis of the roller, and a cable connected to the bail and to said drum for raising and lowering the chute.

30. The combination with the frame of a threshing-machine, of a tilting chute having 95 its free end provided with a revoluble band, means for rotating said band, and a hood pivotally connected to the band and provided with ears projecting beyond its pivot and connected to said means whereby the hood may 100 be rotated or tilted by the same means.

31. The combination with the frame of a threshing-machine, of a tilting chute having its free ends provided with a revoluble band, a hood pivotally mounted on the band and 105 provided with opposite depending ears, a pulley on the chute, and cords having corresponding ends secured to said ears and their opposite ends passed around opposite faces of the pulley for the purpose specified. 110

In witness whereof we have hereunto set our hands this 24th day of January, 1901.

EDGAR P. WATROUS.
LEROY VAN BENSCHOTEN.

Witnesses:

B. R. WILLIAMS,
B. S. WHITMAN.
